UNITED STATES PATENT OFFICE

127,515

DESIGN FOR A COMBINED LAMP, TIMER, AND CONDIMENTS HOLDERS FOR RANGES

William T. Bradbury, Millersport, Ohio, assignor to Newark Stove Company, Newark, Ohio, a corporation of Ohio

Application October 9, 1940, Serial No. 95,703

Term of patent 7 years

To all whom it may concern:

Be it known that I, William T. Bradbury, a citizen of the United States of America, residing at Millersport, in the county of Fairfield and State of Ohio, have invented a new, original, and ornamental Design for a Combined Lamp, Timer, and Condiment Holders for Ranges, of which the following is a specification, reference being had to the accompanying drawing, forming a part thereof.

Fig. 1 of the drawing is a front elevation of a combined lamp, timer and condiment holders for ranges, showing my new design;

Fig. 2 is a plan view of the same; and

Fig. 3 is a right end elevation of the same.

The dominant features of the design reside in the portions shown in full lines.

I claim:

The ornamental design for a combined lamp, timer, and condiment holders for ranges, substantially as shown and described.

WILLIAM T. BRADBURY.
